(57) **CLAIM**

We claim the ornamental design for a front cover for mobile phone cases, as shown and described.

DESCRIPTION

FIG. 1 is a perspective view of a front cover for mobile phone cases showing the new design;

FIG. 2 is a front elevation view thereof;

FIG. 3 is a rear elevation view thereof;

FIG. 4 is a left-side elevation view thereof;

FIG. 5 is a right-side elevation view thereof;

FIG. 6 is a top plan view thereof;

FIG. 7 is a bottom plan view thereof; and,

FIG. 8 is a perspective view thereof in a state of being connected to an unclaimed back cover.

The broken lines in FIG. 8 depict an unclaimed back cover.

1 Claim, 6 Drawing Sheets(56)
